J. D. EICHELBERGER.

IRONING BOARD.

APPLICATION FILED OCT. 2, 1919.

1,381,068.

Patented June 7, 1921.

Inventor:

*John D. Eichelberger,
by Carry Case,
his Atty.*

UNITED STATES PATENT OFFICE.

JOHN D. EICHELBERGER, OF ST. LOUIS, MISSOURI, ASSIGNOR OF ONE-FOURTH TO
EDWARD J. DAMM, OF ST. LOUIS, MISSOURI.

IRONING-BOARD.

1,381,068.

Specification of Letters Patent.

Patented June 7, 1921.

Application filed October 2, 1919. Serial No. 328,039.

To all whom it may concern:

Be it known that I, JOHN D. EICHELBERGER, a citizen of the United States, and a resident of the city of St. Louis and State 5 of Missouri, have invented a new and useful Improvement in Ironing-Boards, of which the following is a specification.

My invention relates to ironing boards and has for its objects to provide a board 10 which can be fastened on to a table, which can be supported at different heights above the table and over which skirts and other garments can be slipped, and to obtain other advantages hereinafter appearing. The invention consists in the parts and combinations of parts hereinafter described and claimed.

In the drawings which form part of this specification and wherein like reference 20 numerals indicate like parts wherever they occur,

Figure 1 is a plan view of an ironing board embodying my invention;

Fig. 2 is a partly sectional view of the 25 same on the line 2—2 of Fig. 1;

Fig. 3 is a sectional view on the line 3—3 of Fig. 1, drawn to a larger scale; and

Fig. 4 is a sectional view on the line 4—4 of Fig. 3.

An ironing board 1 has longitudinal strips 2 along the side margins of its under surface. Blocks 3 are pivotally secured to said strips near the ends thereof. Preferably, said blocks are connected by cross-pieces 4 30 to form a unitary structure adapted to receive members 5 constituting legs for the ironing board. Said legs 5 are slidably disposed in said receiving member by dovetail or tongue and groove joints or other suitable 35 means and are preferably secured together by cross-pieces 6. Said legs have a plurality of transverse holes 7 therein arranged in alining pairs. The blocks also have alining holes 8 therein. A rod 9 extending through 40 a pair of holes of the legs and the holes of the blocks holds the legs in position. The length of the legs can be adjusted by alining different pairs of leg holes with the block holes.

A clamp 10 is provided for fastening the board to a table. It may conveniently be located on the cross-piece connecting the blocks. The ends of the legs and blocks next to the board are rounded so that the

legs can be folded against the board, and 55 the end of the board can be lifted when the board is in use.

The strips have grooves 11 extending a large part of their length. A guide frame 12 has ribs fitting in said grooves. Pivotally secured to this frame are blocks 13 similar to those above described. Leg members 14 are also provided. The blocks and leg members are provided with holes corresponding to the holes of the hereinbefore 60 described legs and blocks, so that the length of the legs can be adjusted to correspond to the lengths of the first mentioned legs. The ends of the legs and blocks are rounded at one corner so that they can be folded 65 over against the board but are preferably left square at the other corner so as to minimize the danger of them folding when the board is in use. The position of the legs can be changed by moving the frame in 70 the grooves.

The ironing board hereinbefore described is adapted to be supported on a table while in use. Among the more important advantages are noted the facts that it may be adjusted to different heights, that one end may be tilted to allow skirts or other garments to be slipped over the board, that one leg may be moved back to allow garments to be slipped over the board without tilting 80 and that the legs can be folded back against the board so that the board takes up comparatively little space when not in use and the danger of the legs being broken is minimized. It is obvious that the construction 85 hereinbefore described may be changed without departing from my invention and I do not wish to be limited to the precise construction shown.

What I claim is:

1. An ironing board having foldable and extensible legs at one end thereof and having longitudinally disposed grooved strips on the under side thereof and foldable and extensible legs at the other end thereof, said 95 legs having portions engaging the grooves in said strips whereby said legs are slidably held, and means for clamping said ironing board to a table or the like.

2. An ironing board having a foldable 100 and extensible support at one end thereof, said support comprising pivotally mounted receiving members and leg members slid-

ably mounted therein and means for securing said leg members at various points of adjustment in said receiving members, a frame movable longitudinally of said ironing board, and a foldable and extensible support on said frame, said support comprising leg members similar to said first

mentioned leg members arranged in pivotally mounted receiving members similar to said first mentioned receiving members. ¹⁰

Signed at St. Louis, Missouri, this 29th day of September, 1919.

JOHN D. EICHELBERGER.
